UNITED STATES PATENT OFFICE.

CHESTER R. GAINS, OF COLFAX, IOWA, ASSIGNOR OF ONE-HALF TO SAMUEL A. POTTS,
OF MUSCATINE, IOWA.

CALL CLOCK.

1,424,092.

Specification of Letters Patent. Patented July 25, 1922.

Application filed June 7, 1921. Serial No. 475,751.

To all whom it may concern:

Be it known that I, CHESTER R. GAINS, a citizen of the United States, and a resident of Colfax, in the county of Jasper and State of Iowa, have invented a new and useful Improvement in Call Clocks, of which the following is a specification.

My invention relates to call clocks and embodies improvements in my application 10 for call clock filed June 16, 1920, Serial No. 389,363 and allowed November 24, 1920.

In the above identified application a vertically movable carriage is provided carrying a rack bar which is fed downwardly 15 step by step by a pair of pivoted pawls.

It is the primary object of the present invention to do away with these pivoted pawls and to provide a simple mechanism for lowering the rack bar step by step.

With these and other objects that may become apparent from the following disclosure the invention consists in the novel combination of elements, construction and arrangement of parts and operations to be 20 hereinafter referred to and explicitly defined in the subjoined claim, the invention being illustrated in the accompanying drawings, wherein,

Figure 1 is a vertical sectional view of the 30 call clock embodying my improvement,

Fig. 2 is an enlarged fragmentary elevation illustrating the rack bar lowering mechanism,

Fig. 3 is a horizontal sectional view taken 35 on line 3—3 of Fig. 2,

Fig. 4 is an enlarged side elevation of the rack bar,

Fig. 5 is a similar view taken at right angles to Fig. 4, and

Fig. 6 is a fragmentary detail view.

My improved call clock denoted generally at 5 is of the same construction as that disclosed in my allowed application above referred to. This clock includes a vertically 40 movable carriage 6 carrying a rack bar 7 and a vertical drive shaft 8, the latter being driven by coacting pinions 9, one of which being fixed to a driven shaft 10 of the clock mechanism 5.

The teeth 11 of the rack bar 7 are beveled 50 at one side on an oblique line with respect to the horizontal as indicated at 12. Fixed to the shaft 8 is a disk 13 provided with a plurality of spaced radially disposed teeth 14 for cooperation with the teeth 12 on the 55 rack bar 7. These teeth 14 are beveled at their edges as indicated at 15 so that the teeth will ride over the beveled edges 12 of the teeth 11 of the rack bar 7 during the rotation of the shaft 8.

In operation it will be obvious that the shaft 8 will be rotated in a clockwise direction by the pinions 9 above referred to and as shown in Fig. 2 the rack teeth 11 of the rack bar 7 rests upon the upper face of the 60 teeth 14. As the disk continues to rotate the teeth 11 will successively drop through the spaces between the teeth 14 so that the rack bar will be lowered step by step at a uniform speed.

It is to be understood that the form of my invention herein shown and described is to be taken as a preferred example of the same, and that various changes in the shape, size and arrangement of parts may be resorted 75 to without departing from the spirit of the invention or the scope of the subjoined claim.

Having thus described my invention, what I claim as new and desire to secure and protect by Letters Patent of the United States is:

The combination with a rotatable shaft, of a longitudinally movable rack bar having the teeth thereof beveled obliquely with respect to the horizontal, at one side thereof, a disk fixed to rotate with the shaft, a plurality of spaced horizontally arranged teeth carried thereby and having their edges beveled so as to pass the beveled face of the 85 teeth on the rack bar, the latter being adapted to successively rest upon the upper face of the disk and to subsequently pass between two adjacent teeth of the latter.

CHESTER R. GAINS.
